UNITED STATES PATENT OFFICE.

PATRICK J. COLLINS, OF PHILADELPHIA, PENNSYLVANIA, ASSIGNOR TO AMERICAN SILENCER COMPANY, OF PHILADELPHIA, PENNSYLVANIA, A CORPORATION OF DELAWARE.

MUFFLER.

1,067,468.

Specification of Letters Patent.

Patented July 15, 1913.

Application filed April 16, 1913. Serial No. 761,522.

To all whom it may concern:

Be it known that I, PATRICK J. COLLINS, citizen of the United States, residing at Philadelphia, in the county of Philadelphia and State of Pennsylvania, have invented 5 certain new and useful Improvements in Mufflers, of which the following is a specification.

This invention relates to a muffler for silencing the exhaust from internal combustion engines and the purpose of the invention is to provide a device of this kind which will be inexpensive to construct and assemble and which will be effective in operation. 10 15 In the accompanying drawing, which illustrates my invention, Figure 1 is a central longitudinal section through the muffler; and Figs. 2, 3, 4, and 5 are transverse sections through the same on the lines 2—2, 20 3—3, 4—4, and 5—5, respectively of Fig. 1.

Referring to the drawing, A indicates the muffler as a whole, comprising a preferably cylindrical inclosing casing 1, having heads 2 and 2^a at its ends, provided with inlet and 25 outlet ports 3 and 3^a, respectively, the former port adapted to be connected to the exhaust pipe of an internal combustion engine. These heads have spiders 4 on their inner sides and they are connected together 30 and clamped against the ends of the casing by a bolt 5 which extends centrally through the casing and through the hubs 4^a of the spiders.

Spaced apart from one another, at suitable intervals throughout the length of the casing, and secured to its inner wall, are baffling partitions 6, 7, 8, and 9. Four partitions are shown in the drawing, but the number may be varied, according to the size 40 of the muffler. These partitions have openings or ports therethrough, indicated at 6^a, 7^a, 8^a, and 9^a, respectively, each opening being eccentric to the longitudinal axis of the casing and preferably of circular form. The 45 successive openings are angularly displaced with respect to one another about the axis of the casing, and preferably this angular displacement is progressive from one end of the series to the other, so that the arrangement of the entire series of openings is spiral. Thus, in the muffler shown in the drawing, having four partitions, it will be seen that the successive openings 6^a, 7^a, 8^a, and 9^a, are arranged progressively 50 degrees apart, so that the gases traveling

through the muffler must necessarily partake of a whirling motion.

The bolt 5 forms a central support for a series of baffling members 10, 11, 12, and 13, in the form of disks of smaller diameter 60 than the openings or ports in the partitions. These disks, it will be seen, are alternately arranged with respect to the partitions, and they are in line with the openings in said partitions, so that the gases, passing through 65 the muffler cannot flow directly from port to port in the partitions, but will be deflected by the central baffling members, which are in line with said ports, and caused to partake of the whirling motion due to the spiral arrangement of the ports or openings in the partitions. The disks 10—13 are preferably of such diameter that, when they are secured to the central supporting rod, the latter, with the disks attached, can be passed 70 through the openings in the partitions, which accordingly facilitates the work of assembling.

In assembling the muffler, the partitions are secured within the casing and the disks 80 are secured to the rod 5. One end of this rod is then connected to the head 2, and the rod with the disks upon it is passed through the openings in the partitions, the head 2 then fitting against the casing. The opposing head 2^a is then placed on the opposite end of the rod and secured thereto in any suitable way, and the two heads are thus clamped tightly against the ends of the casing and the muffler is then ready for use. 90

What I claim is:

1. A muffler comprising an inclosing casing a series of spaced baffling partitions in said casing, each partition having an eccentric opening therethrough, and a series 95 of baffling members of smaller diameter than said openings alternately arranged with respect to said partitions and in line with said openings.

2. A muffler comprising an inclosing 100 casing a series of spaced baffling partitions in said casing, each partition having an eccentric opening therethrough and the openings in the successive partitions being angularly displaced with respect to one another 105 about the axis of the casing, and a series of baffling members of smaller diameter than said openings alternately arranged with respect to said partitions and in line with said openings. 110

- 2
3. A muffler comprising an inclosing casing a series of spaced baffling partitions in said casing, each partition having an eccentric opening therethrough, a support extending through said openings, and a series of baffling members of smaller diameter than said openings secured to said support and alternately arranged with respect to said partitions.
- 5 4. A muffler comprising an inclosing casing a series of spaced baffling partitions in said casing, each partition having an eccentric opening therethrough and the openings in the successive partitions being angularly displaced with respect to one another about the axis of the casing, a support extending through said openings, and a series of baffling members of smaller diameter than said openings secured to said support and
- 10 15 20 5. A muffler comprising an inclosing casing a series of spaced baffling partitions in said casing, each partition having an eccentric opening therethrough and the openings in the successive partitions being angularly displaced with respect to one another about the axis of the casing, a support extending through said openings, and a series of baffling members of smaller diameter than said openings secured to said support and alternately arranged with respect to said partitions.
6. A muffler comprising an inclosing casing a series of spaced baffling partitions in said casing, each partition having an eccentric opening therethrough, and a series of baffling members of smaller diameter than said partitions alternately arranged with respect to said partitions and in line with said openings.

25 30 35 In testimony whereof I have affixed my signature, in presence of two witnesses.

PATRICK J. COLLINS.
